ATTORNEY.

UNITED STATES PATENT OFFICE.

WALTER HILLIER ANDERSON, OF WELLINGTON, NEW ZEALAND, ASSIGNOR TO KINO
LIMITED, OF WELLINGTON, NEW ZEALAND, A CORPORATION OF NEW ZEALAND.

KINEMATOGRAPH APPARATUS.

1,106,069.

Specification of Letters Patent.

Patented Aug. 4, 1914.

Application filed December 4, 1912. Serial No. 734,805.

To all whom it may concern:

Be it known that I, WALTER HILLIER ANDERSON, a citizen of the Dominion of New Zealand, and residing at 318 Willis street, 5 Wellington, in the Provincial District of Wellington, in the Dominion of New Zealand, have invented certain new and useful Improvements in Kinematograph Apparatus, of which the following is a specification.

This invention relates to apparatus used for projecting kinematograph pictures and provides improvements whereby the pictures are more clearly defined upon the screen and 15 the flicker hitherto accompanying the display of kinematograph pictures is considerably reduced.

The improvements are illustrated in the accompanying drawing which will now be 20 referred to for the purposes of a detailed description.

Figure 1, is a side elevation partly in section of a shutter, film gate and tunnel. Fig. 2, a sectional plan on line A—A, Fig. 1, 25 Fig. 3, a perspective view of a cap of a shutter casing and a lens holder, and Fig. 4, a perspective view of the shutter.

Referring to the drawing, the film is fed through a film gate 3 in front of the light 30 from and behind a lens 5, the feeding motion of the film gate being obtained in the ordinary way.

The driving gear of the apparatus is connected by suitable gearing with the spindle 35 45 of a fan or shutter 46 inclosed in a shutter casing 47 fixed to the frame 48 of the machine, and having a cap 49 secured by screws 50. The shutter 46 is cylindrical and has diametrically opposite apertures 51 and 40 52. Bridge pieces 55 and 56 unite the rims 57 and 58 to the rear part 59 of the cylinder. The shutter fits freely within its casing 47 and is adapted to rotate therein.

The cap 49 (see Figs. 2 and 3) carries the 45 lens 5 in a holder comprising a sleeve or bracket 67 mounted upon a slide 68 which is movable laterally for focusing purposes in a groove 70 formed in the cap 49. The back of the slide 68 has a lug 71 fitting a screw 72 50 within a hood 73, knobs 74 and 75 being provided for turning the said screw 72 and thereby focusing the lens.

The casing has apertures 76 and 77 for the admission and emission respectively of 55 light to the lens from the lantern house 4.

The film gate 3 (see more particularly Figs. 1 and 2) is pivoted by screws or pins 81 and 82 to brackets 83 and 84 extending laterally from a slide 86, slideable in grooves formed in the back of the casing 47. Friction bars 89 and 90 carried by the gate 3 consist of wires having their ends bent at a right angle and passing through the gate. Flat springs 91 and 92 are secured to the gate at their middle part by screws 93 and 94 and 65 bear respectively upon the upper ends 95 and the lower ends 96 of the friction bars 89 and 90 insuring an equal pressure upon the lateral sides of the film. When the film gate is closed upon its mouthpiece 97, the 70 bars 89 and 90 enter the recess 98 of the mouthpiece and bear upon the film with equal pressure, owing to the springs 91 and 92 being secured at their middle part as described. The gate is held in its closed position by means of slides 100 and 101, which have slots 102, whereby they are slideable upon screws 103. Catches 104 and 105 upon the slides are adapted to engage lugs 106 and 107 formed upon the gate 3. 75

The slides 100 and 101 are operable by a button 108 secured upon a spindle 109 which is provided with arms 110 engaging notches formed in the slides 100 and 101. The slide 86 is fixed to the mouthpiece 112 of the tunnel 113 of the lantern house. Within this tunnel is arranged a fall down safety shutter 114 which automatically controls the admission of light from the lantern. 80

The film is readily placed in position within the film gate by withdrawing the termination of the tunnel 113, which telescopes upon the base 126 of the tunnel. The film is thus merely passed laterally into position into the gate 3 without the necessity of 90 threading the film endwise through these parts. By fixing the mouthpiece 112 to the slide 86 the end of a broken film is prevented from entering the tunnel and being ignited by the lamp. 95

What I do claim and desire to secure by Letters Patent of the United States is:—

1. In kinematograph apparatus, a cylindrical casing having opposite apertures, a cap upon the casing, a sleeve upon the inner face of the cap, a lens carried in the sleeve, a cylindrical shutter surrounding the lens and located in said casing and having apertures and blanks, and means for rotating the shutter. 105

2. In kinematograph apparatus, a cylindrical casing having opposite apertures, a cap upon the said casing and having a groove, a slide fitting the groove, a sleeve carried by the slide, a lens carried in the sleeve, means for moving the slide laterally, a cylindrical shutter surrounding the lens and located in said casing and having apertures and blanks and means for rotating the shutter.

3. In kinematograph apparatus, a cylindrical casing having opposite apertures, a cap upon the said casing and having a groove, a slide fitting the groove, a sleeve carried by the slide, a lens carried in the sleeve, a lug upon the slide, a hood covering the lug, a screw passing through the hood and screwed into the lug, a cylindrical shutter surrounding the lens and located in said casing and having apertures and blanks and means for rotating the shutter.

4. In kinematograph apparatus, an apertured casing, an apertured shutter located therein, means for rotating the shutter, a mouthpiece on the casing, a slide having brackets adapted to be moved toward and from the mouth piece, a film gate pivoted to said brackets, and means for attaching the film gate to the mouth piece of the said casing.

5. In kinematograph apparatus, an apertured casing, an apertured shutter located therein, means for rotating the shutter, a mouthpiece on the casing, a slide having brackets adapted to be moved toward and from the mouth piece, a film gate pivoted to said brackets, vertical friction bars having right-angled ends passing through the gate, horizontal springs projecting the top ends and lower ends respectively of the said bars through the gate and means for attaching the gate to the mouthpiece.

6. In kinematograph apparatus an apertured shutter casing, an apertured shutter located therein, means for rotating the shutter, a mouthpiece on the casing, a slide having brackets adapted to be moved toward and from the mouthpiece, a film gate pivoted to said brackets, vertical friction bars having right-angled ends passing through the gate, horizontal flat springs secured to the gate at their middle part and having their

ends bearing upon the ends of the friction bars, and means for attaching the gate to the mouthpiece.

55

7. In a kinematograph apparatus an apertured shutter casing, an apertured shutter located therein, means for rotating the shutter, a mouthpiece on the casing, a slide having brackets thereon adapted to be moved toward and from the mouthpiece, a film gate pivoted to said brackets, slides upon the mouthpiece, a spindle carried by the casing, arms on said spindle adapted to engage slots in the mouthpiece slides, and catches upon the film gate adapted to be engaged by the slides.

8. In kinematograph apparatus an apertured casing, an apertured shutter located therein, means for rotating the shutter, a mouthpiece on the casing, a slide, having brackets thereon adapted to be moved toward and from the mouthpiece, a film gate pivoted to said brackets, slides upon the mouthpiece, a spindle carried by the casing, arms on said spindle adapted to engage slots in the mouthpiece slides, catches upon the film gate adapted to be engaged by the slides, and a telescopic tunnel through which the light enters, the termination of the tunnel being fixed to the first-mentioned slide.

9. In kinematograph apparatus, an apertured shutter casing, an apertured shutter located therein, means for rotating the shutter, a mouthpiece on the casing, a slide having brackets thereon adapted to be moved toward and from the mouthpiece, a film gate pivoted to said brackets, slides upon the mouthpiece, a spindle carried by the casing, arms on said spindle adapted to engage slots in the mouthpiece slides, catches upon the film gate adapted to be engaged by the slides, a telescopic tunnel through which the light enters, the termination of the tunnel being fixed to the first-mentioned slide, and a fall down safety shutter within the tunnel.

In testimony whereof I have signed my name to this specification in the presence of two witnesses.

WALTER HILLIER ANDERSON.
